GEORGE D. WIDMAN, OF LOS ANGELES, CALIFORNIA

SOAP DISPENSER

Application filed January 13, 1930. Serial No. 420,407.

This invention relates to a dispenser for material of a jelly-like nature, such as jelly soap. More specifically, it appertains to a dispenser operable by a person to deliver a predetermined quantity of soap.

It is the primary object of this invention to provide a manually operable dispenser which is manually operable and may be actuated to deliver the dispensed soap to the palm of the hand of the operator. Another object of this invention is to provide a dispenser operable by twisting an actuating member to a degree such that a desired amount of soap is delivered, the greater the amount actuator is turned, the greater the quantity of soap delivered. A further object of this invention is to provide a dispenser of the class described having details of structure such that a simple device, economical to manufacture, compact and easily operated is obtained.

These objects together with other objects and corresponding accomplishments are obtained by means of the embodiment of my invention illustrated in the accompanying drawings, in which:

Fig. 1 is an axial sectional view through a dispenser embodying my invention; Fig. 2 is a section as seen on the line 2-2 of Fig. 1; and Fig. 3 is a section of a fragment of the dispenser as seen on the line 3-3 of Fig. 1.

Referring more particularly to the drawings, a shell for a charge of soap is indicated by 5. This shell may have brackets 6 secured thereto for mounting the dispenser upon a wall or like support. The lower end of the shell flares inwardly and downwardly to provide a tapered lower end. As shown herein, the lower end has an external flange 8 to receive a lip 9 formed on the bottom 10. The construction is such that the bottom may be rotated upon the shell and any other convenient means for mounting the bottom rotatably upon the shell may be resorted to. Formed in the bottom 10 is a slotted opening 11 for the delivery of the soap to be dispensed. Ranging upwardly from the slot 11 is a shaving trough 12. This trough overlies the inner wall of the lower end 7 of the shell, and is inclined forwardly in the direction in which it is intended that the bottom 10 should be

rotated to form a flight. The construction is such that when the bottom is rotated in the direction of the arrow A, the scraping trough will scrape soap from the tapered end of charge and direct the shaving downwardly through the discharge opening 11. This will cause the tapered end of the charge to be reduced in size and the charge will tend to advance downwardly into the tapered end 7 and fit the latter. A lip 13 at slot 11 is provided to scrape off soap from the end and deliver it through the opening 11. Lip 13 provides for delivering the main portion of the soap dispensed permitting the charge of soap to advance toward the bottom.

The dispenser is filled with soap of a jelly-like consistency, so that it will not drop through the discharge opening 11 but must be positively advanced. In order that the charge of soap may be caused to feed as it is scraped from the end, a follower plate 14 is provided. This plate is in the nature of a piston. Secured to the upper face of the piston is a compression spring 15, which spring is of helical form and tapers toward the top. Thus, the coils of the spring when compressed may lie within one another. The upper end of the spring is secured to a cover 16 for the shell. This cover may be of the slip-on type and locked in position by a bayonet slot and pin indicated generally by 17.

In order to fill the dispenser, the cover 16 is removed and with it the follower plate 14. A charge of soap is then placed in the dispenser. The follower plate is then inserted in the shell and the cover 16 secured in closed position. The tension of spring 17 urges the follower against the charge of soap and tends to advance the charge toward the bottom. In order to hold the charge against rotation, a fin 18 is provided on the lower face of the follower plate and imbeds itself in the soap.

A person desiring soap grasps the bottom plate 10 straddling it with his fingers. The palm of his hand then lies underneath the discharge opening 11. The bottom is then turned in the direction of the arrow A. This causes the scraping lip to cut soap from the bottom of the charge and the trough to be revolved and to scrape soap from the taper-

ing end of the charge directing the scraping downwardly and through the discharge opening 11 into the hand of the operator and providing for advance of the charge. The 5 amount of soap so delivered will depend upon the angle through which the bottom is turned. The follower 14 causes the advance of the charge toward the bottom as the soap is delivered. Fin 18 restrains the charge of soap 10 from revolving and thereby insures that it will be scraped from the lower end. Although I have shown the bottom 10 rotatably secured to the shell, it is obvious that the rotational bearing may be located higher.

15 What I claim is:—

1. A soap dispenser for a jelly like charge comprising a reservoir shell with a rotatable bottom section adapted to be gripped and to overlie the palm of the hand, said shell having 20 a tapered lower end, a discharge opening in said bottom section, a scraping lip at the margin of said opening whereby to scrape material to be dispensed from the bottom end of the charge material in said dispenser and direct it through said opening, a scraping 25 flight fixed to said bottom section and ranging from said discharge opening upwardly along the tapered wall of said shell and forwardly in relation to the intended rotation 30 whereby to scrape the material to be dispensed and direct it toward the opening, and means urging the charge of material toward the bottom of said dispenser.

2. A soap dispenser for a jelly like charge 35 comprising a reservoir shell with a rotatable bottom section adapted to be gripped and to overlie the palm of the hand said shell having a tapered lower end, a discharge opening in said bottom end section, a scraping lip 40 at the margin of said opening whereby to scrape material to be dispensed from the bottom of the charge material in said dispenser and direct it through said opening, a scraping flight fixed to said bottom section and 45 ranging from said discharge opening upwardly and forwardly in the direction of rotation along the tapered wall of said shell whereby to scrape the material to be dispensed and direct it toward the opening, a follower plate 50 resting on the charge of material in said dispenser, and means urging said follower against said charge to cause said charge to be advanced toward the bottom of said dispenser.

55 3. A soap dispenser for a jelly like charge comprising a reservoir shell with a rotatable bottom section adapted to be gripped and to overlie the palm of the hand, said shell having a tapered lower end, a discharge opening 60 in said bottom end section, a scraping lip at the margin of said opening whereby to scrape material to be dispensed from the bottom of the charge material in said dispenser and direct it through said opening, a shaving 65 trough fixed to said bottom section and rang-

ing from said discharge opening upwardly and forwardly in the direction of rotation along the tapered wall of said shell whereby to scrape the material to be dispensed and direct it toward the opening, a follower plate 70 resting on the charge of material in said dispenser, means urging said follower against said charge to cause said charge to be advanced toward the bottom of said dispenser, and means to restrain the charge against rotation with the bottom section.

4. A soap dispenser for a jelly like charge comprising a reservoir shell with a rotatable bottom section adapted to be gripped and to overlie the palm of the hand, said shell having a tapered lower end, a discharge opening in said bottom section, a scraping lip at the margin of said opening whereby to scrape material to be dispensed from the bottom end of the charge of material in said dispenser 80 and direct it through said opening, a scraping flight fixed to said bottom section and ranging from said discharge opening upwardly and forwardly in the direction of rotation along the tapered wall of said shell whereby to scrape the material to be dispensed and direct it toward the opening, a follower plate 85 resting on the charge of material in said dispenser, a detachable cover for said shell, a compression spring secured to said cover and to said follower to urge said follower against said charge and cause said charge to be advanced toward the bottom of said dispenser.

5. A soap dispenser for a jelly like charge comprising a reservoir shell with a rotatable bottom section adapted to be gripped and to overlie the palm of the hand, said shell having a tapered lower end, a discharge opening in said bottom section, a scraping lip at the margin of said opening whereby to scrape material to be dispensed from the bottom end of the charge of material in said dispenser and direct it through said opening, a scraping flight fixed to said bottom section and ranging from said discharge opening upwardly and forwardly in the direction of rotation along the tapered wall of said shell whereby to scrape the material to be dispensed and direct it toward the opening, a follower plate resting on the charge of material in said dispenser, means urging said follower against said charge to cause said charge to be advanced toward the bottom of said dispenser, and a transverse fin on said follower plate to restrain the charge against rotation with the bottom section.

6. A soap dispenser for a jelly like charge comprising a reservoir shell with a rotatable bottom section adapted to be gripped and to overlie the palm of the hand, said shell having a tapered lower end, a discharge opening in said bottom section, a scraping flight fixed to said bottom section and ranging from said discharge opening upwardly and forwardly in the direction of rotation along the tapered

wall of said shell whereby to scrape the material to be dispensed and direct it toward the opening, and means urging the charge of material toward the bottom of said dispenser.

5 7. A soap dispenser for a jelly like charge comprising a reservoir shell with a rotatable bottom section adapted to be gripped and to overlie the palm of the hand said shell having a tapered lower end, a discharge opening in
10 said bottom section, a scraping flight fixed to said bottom section and ranging from said discharge opening upwardly and forwardly in the direction of rotation along the tapered wall of said shell whereby to scrape the material to be dispensed and direct it toward the opening, a follower plate resting on the charge of material in said dispenser, and means urging said follower against said charge to cause said charge to be advanced
15 20 toward the bottom of said dispenser.

8. A soap dispenser for a jelly like charge comprising a reservoir shell with a rotatable bottom section adapted to be gripped and to overlie the palm of the hand, said shell having a tapered lower end, a discharge opening in said bottom section, a scraping flight fixed to said bottom section and ranging from said discharge opening upwardly and forwardly in the direction of rotation along the tapered wall of said shell whereby to scrape the material to be dispensed and direct it toward the opening, a follower plate resting on the charge of material in said dispenser, means urging said follower against said charge to cause said charge to be advanced toward the bottom of said dispenser, and means to restrain the charge against rotation with the bottom section.

9. A soap dispenser for a jelly like charge comprising a reservoir shell with a rotatable bottom section adapted to be gripped and to overlie the palm of the hand, said shell having a tapered lower end, a discharge opening in said bottom section, a scraping flight fixed to said bottom section and ranging from said discharge opening upwardly and forwardly in the direction of rotation along the tapered wall of said shell whereby to scrape the material to be dispensed and direct it toward the opening, a follower plate resting on the charge of material in said dispenser, a detachable cover for said shell, a compression spring secured to said cover and to said follower to urge said follower against said charge and cause said charge to be advanced toward the bottom of said dispenser.

In witness that I claim the foregoing I have hereunto subscribed my name this 28th day of December, 1929.

60 GEORGE D. WIDMAN.
